GAS TURBINE RAILWAY CAR

Joseph F. Clary, Gladwynne, Pa., John D. Cuccio, Westport, Conn., and Albert G. Dean, Narberth, Norman W. Esmire, Huntingdon Valley, Taylor D. MacLafferty, Wynnewood, William L. Sheppard, Huntingdon Valley, and Paul O. Sichert, Jr., and Joel H. Squier, Wynnewood, Pa., assignors to The Budd Company, Philadelphia, Pa., a corporation of Pennsylvania

Filed July 28, 1965, Ser. No. 86,330

Term of patent 14 years

(Cl. D66—1)

FIG. 1 is a side elevational view;
FIG. 2 is a side perspective view;

The side and end opposite that shown in FIG. 2 is the same in appearance as the side and end shown.

The dominant features of our design are shown in full lines.

We claim:

The ornamental design for a gas turbine railway car, as shown and described.
